UNITED STATES PATENT OFFICE.

CHARLES J. DUNTON, OF ORCUTT, CALIFORNIA.

SHALE RETORT.

Application filed October 4, 1922. Serial No. 592,366.

To all whom it may concern:

Be it known that I, CHARLES J. DUNTON, a citizen of the United States, residing at Orcutt, in the county of Santa Barbara and 5 State of California, have invented certain new and useful Improvements in Shale Retorts, of which the following is a specification.

This invention relates to apparatus for 10 the heat treatment of oil bearing shale and similar hydrocarbon oil containing materials and pertains particularly to an improved form of gate-valve to be used in the receiving and discharge passageways 15 for said apparatus and is particularly adapted to such an apparatus within which the heat is generated by burning a portion of the material within the apparatus.

One feature of the invention is the particular construction of the slidable member 20 of the gate-valve. Experience has shown that in all types of hopper or passageway valves heretofore used, a serious drawback to their successful operation has been the 25 accumulation of tarry matter and deposits on the moving parts and the result has been that shale apparatus so equipped is unable to render continuous service. Troubles common to the previously known apparatus of 30 this type are avoided by the details of the present invention in which the valve opening in the slidable member bears a definite proportion to the area of the whole member and when a plurality of valves are used, 35 the openings in each separate valve are alternated thus preventing a breaking of the seal at the receiving and discharge ends.

The invention further provides mechanically operated driving means for the valves, 40 said driving means being positioned adjacent the main apparatus and being connected to all the valves in use so that one source of power will serve to actuate the driving means and thereby operate the 45 valves simultaneously.

The above mentioned and other features of the invention will be described in detail and claimed in the following specification and claim and illustrated in the drawings, 50 in which:

Figure 1 represents a vertical sectional view through the preferred form of apparatus;

Figure 2 is a vertical cross sectional view 55 taken on the line 2—2 of Figure 1 and illustrates the arrangement of the slidable mem-

ber of the valve with respect to the stationary member thereof;

Figure 3 is a horizontal cross sectional view taken on line 3—3 of Figure 2, showing the position of the opening in the slid- 60 able valve member; and

Figure 4 is an exterior view of an apparatus in which the improved form of valves is used. 65

Referring now to Fig. 1, 1 represents the main body of the shale retort and may be made in accordance with any of the well known designs for such apparatus. The distilling zone is represented by 2 and the 70 same is positioned intermediate the receiving passageway 4 and the discharge passageway 6. The upper portion of receiving passageway 4 has mounted thereon a hopper 3, said hopper being formed with sloping sides and 75 having a horizontal partition 8 placed across the narrowest portion of its throat. Midway within the passageway 4 is positioned an auxiliary hopper 5 which also has sloping sides. This hopper has a horizontal 80 partition 9 placed across the narrowest portion of its throat, said partition extending to the sides of the passageway 4. The partitions 8 and 9 lie wholly within passageway 4 and are in spaced relation with each other. 85 The partitions 8 and 9 have rectangular openings 15 and 16 cut through them, the width of said openings with respect to the partitions being shown in the drawing. These openings lie directly in the center line of the passageway 4. Similar partitions 12 and 13 are positioned in the discharge passageway 6. As shown more clearly in Figure 2 there are positioned below the horizontal partition 8, horizontal 90 parallel guide members or tracks 11 upon which the member 10 is caused to slide. These guide members are secured to the sides of the hopper 4 and are spaced from the horizontal plate by a space equal to 100 the thickness of the slidable plate 10. This plate is of a smaller horizontal sectional area than the horizontal sectional area of the passageway 4. As shown in Figure 3, the slidable member has an opening 17 cut 105 therethrough. This opening is of rectangular form and is positioned to one side of the center line of the slidable member and in practice, this opening will bear a definite proportion to the total area of the slidable member and will also be of the same size 110 as the opening 15 in the horizontal parti-

tion 8. The member 10 has a connecting rod 14 extending therefrom in a horizontal direction, through the wall of the hopper this rod being of a length sufficient to engage a vertical crank shaft 19 positioned to one side of the apparatus. The slideable members 23, 24 and 25 are of the same dimensions as the slideable member or gate valve 10 and each is supported and positioned in substantially the same manner. The respective connecting rods 21, 22 and 20 also connect with the crank shaft 19. The crank shaft 19 which is mounted adjacent to the apparatus is continuously rotated through a gear 26 in mesh with a gear 26^a which latter is on a shaft 26^b driven by a source of power, not shown. The various connected rods being connected to the crank shaft are therefore given an alternate motion, the crank arms being so thrown that when gate valve 10 is moved in the guide members and opening 17 registers with opening 15, the gate valve 25 is moved in the opposite direction and the openings 16 and 18 do not register. Similar alternate motions are applied to the gate valves 23 and 24. It will therefore be seen that as the material is fed into the receiving passageway the upper end of the distilling chamber is always closed to the admission of air. Similarly, as the spent shale is being discharged through the discharge passageway, the lower end of the distilling chamber is closed to the air. The slideable members serve to shear off or clear away any tarry matter that accumulates around the valve openings and the sliding motion on the tracks or guiding members has a tendency to keep the same clear of all deposits that may form. Moreover, the novel construction of the gate-valves obviates the attendant losses in heat during the time of operation.

The entire process is familiarly known as the continuous process of distillation, steam

being admitted at 28 and the vapors from the distilling chamber passing off through the pipe 29. The spent shale is dumped from the lowermost valve and may be led off by an inclined chute or carted away. Tap holes 30 (see Figs. 1 and 4), are provided in the casing 1 by means of which stirring rods may be inserted into the body of the shale.

As stated elsewhere in the specification, the opening 17 in the slideable member 10 bears a definite proportion to the total area of the slideable member. This proportion is obtained by constructing the opening 17 with a width substantially less than half the longitudinal dimension of the slideable member thereby giving an opening of less area than the imperforate portion of the slideable member. The imperforate portion of the member is sufficient to completely cover opening 15 in the horizontal partition of the passageway.

I claim:

In an apparatus having a distilling chamber for extracting hydrocarbon oils from shale and similar material, means for introducing shale in successive charges to the upper end of said chamber, said means comprising a receiving passageway, a plurality of horizontal gate valves in spaced relation with each other disposed in said passageway, means for removing spent shale from the lower end of said chamber, said means comprising a discharge passageway, a plurality of horizontal gate valves in spaced relation with each other disposed in said passageway, a vertical rotatably driven crank shaft positioned adjacent to said apparatus, and means on said shaft adapted to engage said gate valves to alternately operate said valves for the admission and discharge of shale.

In testimony whereof I affix my signature.

CHARLES J. DUNTEM
